WILLIAM S. CALLAHAN, ALL OF LOS ANGELES, CALIFORNIA

BRIQUETTING MACHINE

Application filed October 22, 1930, Serial No. 490,450. Renewed November 12, 1932.

My invention relates to machines for forming briquettes from finely divided material, such as briquettes made from sawdust, coal-dust, or other similar materials.

5 An object of my invention is to provide a machine for forming briquettes from finely divided material in which a single die constituting a plurality of molds may be rotated to bring the molds into coincidence with a plurality of plungers for operating the various compressive steps in the forming of the briquettes.

10 Another object of my invention is to provide a briquetting machine of the character described in which molds are so spaced around the axis of rotation of the rotatable die that a single operation of compression plungers will fill one mold with raw material, compress the raw material in another mold, will permit the heating or drying of the material in the third mold, and will eject the finished briquettes from a fourth mold.

15 Another object of my invention is to provide a briquetting machine in which the several successive steps to be performed upon the raw material will be accomplished in cycles so that at any given instant in the operation of the machine there will be briquettes in each of the several steps of formation.

20 Another object of my invention is to provide a briquetting machine in which a rotatable die carrying a plurality of molds may be acted upon by plungers coincident with the molds, and in which the motive power for reciprocating the plunger to form the briquettes is also utilized to rotate the die during the periods of retraction of the plungers.

25 Other objects of my invention will be apparent from the following description read in connection with the accompanying drawing, in which

Figure 1 is a top plan view of my briquetting machine.

30 Figure 2 is a side elevational view of the machine illustrated in Figure 1.

Figure 3 is a detailed view of the rotatable die; and

Figure 4 is a detailed view of the intermittent driving mechanism which is utilized to intermittently rotate the die.

Referring to the drawing, I have illustrated my briquetting machine as comprising a base or bed-plate 1 upon which are found a pair of upstanding guides 2 and 3 upon which is mounted, for horizontal reciprocation, a plunger-carrying head 4. The plunger-carrying head is of relatively square lateral cross section and has secured thereto a plurality of plungers for the purpose of pressing and ejecting briquettes of material to be formed by the machine.

35 I have illustrated along the lower edge of the plunger head 4 a pair of compressor plungers 5 and 5a (5a not shown) which are rigidly secured to the plunger head 4 in any suitable manner so that reciprocation of the plunger head causes a reciprocation of the plungers 5 and 5a through a distance equal to that through which the plunger head 4 moves.

40 Along one side (the upper side illustrated in Figure 1), I have illustrated an additional pair of plungers 6 and 6a, also rigidly secured to the plunger head 4 for movement therewith, these plungers 6 and 6a constituting ejector plungers which are of considerably greater length than the plungers 5 and 5a. Along the upper edge of the plunger head 4 (as illustrated in Figure 2), I have illustrated a pair of tamper plungers or filler plungers 7 and 7a, these plungers being loosely mounted in the reciprocating head 4, being guided by means of an upstanding lug 8 through which the rearward ends of the plungers 7 and 7a pass.

45 The plunger carrying head 4 is connected as by means of a wristpin 9 and a connecting rod 10 to an eccentric 11 which in turn is mounted upon and rotates with a shaft 12. The shaft 12 is journaled in suitable bearings

13 located in a rearwardly extending portion 14 and 15 of the upstanding guides 2 and 3, respectively.

The foregoing construction constitutes a 5 reciprocating plunger carrying system in which rotation of the shaft 12 will cause the plungers 5 and 5a, 6 and 6a, 7 and 7a to be reciprocated between an extreme rearward position and an extreme forward position 10 upon each revolution of the shaft.

Immediately in advance of the plunger carrying head 4 is a plunger guide block 16 which is provided with suitable openings coinciding with the plungers 5-7a, inclusive. 15 The plungers 5 and 5a operate in suitable openings 5b and 5c, respectively, the plungers 6 and 6a operating in suitable openings 6b and 6c, while plungers 7 and 7a operate through a pair of openings 7b and 7c, respectively. 20 Immediately above the openings 7b and 7c I have illustrated a hopper 17 through which the material to be formed into briquettes may be fed into the plunger guide block 16 in a position to be pressed into a die block 18, located immediately in advance 25 of the plunger guide block 16.

By referring particularly to Figure 3, it will be observed that I have illustrated the die block 18 as being provided with a plurality of relatively large cylindrical openings therethrough, these openings constituting the molds into which the material to be formed into a briquette may be fed and there compressed to the size and shape desired.

30 The molds are arranged around the die block 18 in groups of four, thus molds 19, 20, 21 and 22 constitute one group in which the individual molds are equally spaced around a circle having the center or axis 23 of the die block 18 as its center. In other words, the group of molds constituted by molds 19, 20, 21 and 22 are distributed at 90° apart around the face of the die block 18. A second group of molds is illustrated as comprising molds 45 19a, 20a, 21a and 22a, which are in like manner spaced equally around the axis 23 of the die block 18. The die block 18 is illustrated as being rigidly secured to an axle 24, which is mounted for rotation under the influence 50 of an intermittent gearing 25 illustrated as comprising a Geneva cross movement, the star 26 being secured to the axle or shaft 24 while the cam and pin portion 27 of the Geneva movement is illustrated as being secured to a shaft 28. The relationship of the star 26 to the position of the molds 19, 19a, etc., is such that at any position of rest of the star wheel 26 one pair of molds (for example, 19, 19a) are aligned with the openings 7b and 7c through which the tamper or 60 filler plungers 7 and 7a operate.

By referring to Figure 3, it will be observed that with molds 19 and 19a in this position, molds 21 and 21a will be in such 65 position as to be in alignment with the open-

ings 5b and 5c through which the plungers 5 and 5a operate, while, at the same time, molds 22 and 22a will be in alignment with the ejector plungers 6 and 6a.

If the die block 18 is rotated by the Geneva cross movement 25 to its next position, the molds 22 and 22a will move into the position previously occupied by molds 19 and 19a, while the remainder of the molds will also assume positions 90° in advance of the positions illustrated in Fig. 3. Further rotation of the die block 18 through the intermittent gearing 25 will successively present the molds 21-21a and molds 20-20a, in the positions opposite the filler or tamper plungers 7 and 7a. With any selected pair of molds in position in front of the filler or tamper plungers 7 and 7a, the remaining molds are in positions coinciding with the other plungers 6-6a and 5-5a.

Since the molds 19-22a extend entirely through the mold or die block 18, it is necessary that the forward end of the molds shall be closed at a time when the plungers 7 and 7a are filling them with material and also at the time when the compressor plungers 5 and 5a are compressing the material in the molds, and for this reason, I have provided an anvil 30 which is secured to the bedplate 1 at the position just in advance of the die block 18 and has formed thereupon a plurality of rearwardly extending bosses 31 and 32 in such positions relative to the die block 18 as to close the uppermost and lowermost pairs of molds at any given position of rest of the die block 18. If desired, the anvil 30 may be utilized as a bearing or journal member for supporting the shaft 24 which carries the die block 18.

It will be observed that a portion of one side of the anvil 30 is cut away to accommodate the inwardly turned end 33 of an ejection chute 34 to be brought into alignment with the ejection chambers 6 and 6a to receive the briquetted material when the same is ejected from the die block 18 by the ejector plungers.

The shaft 28, to which the pin and cam section 27 of the Geneva cross movement is secured, is illustrated as being connected as by means of bevel gearing 35 to the same shaft 12 which carries the eccentric 11. The shaft 12 may be driven in any suitable manner, such as that illustrated, comprising a pulley 36 secured to the shaft 12 to be driven by means of a suitable belt 37 arranged to be driven by means of an electric motor or any other rotary source of movement.

My invention operates as follows: Assuming that the position of the die block 18 is that illustrated in Figure 3, that the molds 19 and 19a are in alignment, respectively, with the filler openings 5b and 5c, and assuming that the material to be briquetted, such as sawdust mixed with a suitable liquid or semi-

liquid binder is fed into the hopper 17, such material will flow down into the openings 5b and 5c. Thus upon starting rotation of the pulley 36 to drive the shaft 12 the movement 5 of the eccentric 11 will cause a movement of the plunger carrying head 4 toward the right, as illustrated in Figure 1. Such movement will cause the plungers 7 and 7a to move into the openings 5b and 5c, respectively, to displace the material therefrom and force such material into the mold openings 19 and 19a in the die block 18. 10

By referring, particularly, to Figures 1 and 2, it will be observed that I have provided 15 against excessive filling of the molds 19 and 19a by mounting the plungers 7 and 7a loosely upon the plunger head 4. The movement of the plungers to the right will be only such movement as is necessary to completely fill 20 the molds 19 and 19a. When these molds are filled, and therefore exert resistance against further movement of the plungers 7 and 7a, the plungers cease to move, even though the plunger head 4 may not have completed its 25 full movement toward the right.

By referring, particularly, to Figure 1, it will be observed that each of the plungers 7 and 7a is provided with a collar 38 which may be pinned or otherwise suitably secured to 30 the plungers. Between the collar 38 and the guide lug 8, through which the plungers pass, I have illustrated a compression spring 39 for each of the plungers. Thus the extent of movement of the plungers 7 and 7a in their 35 filling or tamping action is limited to just such distance as is required to fill the molds and any further movement of the plunger carrying head 4 will be independent of further movement of the plungers 7 and 7a. By securing the rearward ends of the plungers 7 and 7a, as by means of adjusting nuts 40, the length of the actual stroke which is to be given to each of the plungers may be suitably 40 adjusted to insure complete filling of the molds, and to insure that the quantity of material pressed upon by the plunger will not be greater than that which is desired to be placed in the molds. 45

The molds 19 and 19a having been filled, 50 the further rotation of the shaft 12, under the influence of the belt 37 and pulley 36, will cause the connecting rod 10 to retract the plunger carrying head 4 and to withdraw the plungers 7 and 7a to permit further molds to flow from the hopper 17 into the openings 5b and 5c, ready for the next charging stroke of the filler or tamper plungers. 55

By properly selecting the relationship of 60 the gears 35 and by properly setting the Geneva cross movement, the rearward movement of the plunger head 4 will be accompanied by a rotation of the die block 18 through a quarter revolution. This quarter revolution will move the now filled molds 19

and 19a to the position which had previously been occupied by molds 20 and 20a. 65

It may be desirable, in the treatment of certain materials which are to be formed into briquettes, to apply heat during the 70 briquetting process and for this purpose I have illustrated a heater pipe 41 as arranged on the side of the briquetting machine with its nozzle 42 directed against the side of the die block 18 adjacent the positioning of the 75 molds 20 and 20a, (when the die block is in position illustrated in Figure 3).

The further rotation of the shaft 12 will again move the plunger head 4 toward the 80 right, bringing the plungers 7 and 7a also to the right to force the material from the hopper 17 into the further side of molds 22 and 22a, which are now in a position opposite to the plungers 7 and 7a. 85

Upon retracting the plunger head 4, the 90 Geneva cross gearing will cause the die block 18 to again be rotated to a quarter revolution, placing the now filled molds 22 and 22a in a position adjacent the heater pipe 41 and moving the molds 19 and 19a, (which 95 have now been dried or cured as the result of the heat applied), to a position previously occupied by molds 21 and 21a, (in the position shown in Fig. 3). 100

With the molds 19 and 19a in the lowermost position, they are aligned with the compressor plungers 5 and 5a so that upon the next forward movement of the plunger head 4, the plungers 5 and 5a, which are of considerably greater length than the filler plungers 7 and 7a, will enter the molds 19 and 19a and compress the material therein into a compact mass or briquette. However, this forward movement of the plunger head compresses the material in molds 19 and 19a and also causes the molds 21 and 21a (which are now adjacent the plungers 7 and 7a), to be filled with the material to be treated. 105 110

Upon recession of the plunger head 4, the die block 18 will again be rotated through a quarter revolution to present molds 19 and 19a to the ejector plungers 6 and 6a, so that upon the next forward movement of the plunger head 4, the ejector plungers 6 and 6a will enter the molds 19 and 19a and eject the briquetted material therefrom. 115

It will be observed that the ejector plungers 6 and 6a are of considerably greater length than the compressor plungers 5 and 5a 120 so that upon the forward movement of the plunger head 4 the plungers 6 and 6a will extend entirely through the die block 18, thus forcing the briquetted material from the die block into the passage 33 from which the material may be taken from the machine through the ejector chute 34. 125

It will be observed, therefore, that my machine will automatically feed material into the molds, cure the material, compress the 130

material into a briquette, and finally eject the briquetted material therefrom.

The employment of the die block 18 and the series of plungers all carried by the single plunger head 4, insures that upon each stroke of the plunger head 4 one of the four steps will be performed upon each four materials constituting each group of molds. Hence the machine once started continues in operation to produce briquetted material in a continuous process.

While the form of my invention illustrated is the preferred embodiment, I do not desire to be limited to any of the details shown and described herein, except as defined in the appended claims.

I claim:

1. In a briquetting machine, a rotatable die having a plurality of briquette molds extending therethrough, said molds being arranged in groups of four molds each and spaced equidistant around the axis of said die, a set of reciprocating plungers for each group of molds, each set including a tamper plunger, a compressor plunger and an ejector plunger, said plungers being spaced around the axis of said die coincident with the first, third and fourth molds of each group respectively, means for reciprocating said plungers toward and away from said die, and rotating said die in intermittent steps of a partial revolution each to bring any given mold from a position coincident with one plunger to a position coincident with another plunger, said rotation occurring during the movement of the plungers away from the die.

2. In a briquetting machine, a rotatable die having a plurality of briquette molds extending therethrough, said molds being arranged in groups of four molds each and spaced equidistant around the axis of said die, a set of reciprocating plungers for each group of molds, each set including a tamper plunger, a compressor plunger and an ejector plunger, said plungers being spaced around the axis of said die coincident with the first, third and fourth molds of each group, respectively, means for reciprocating said plungers toward and away from said die, and rotating said die in intermittent steps of a partial revolution each to bring any given mold from a position coincident with one plunger to a position coincident with another plunger, said rotation occurring during the movement of the plungers away from the die, and a stationary anvil abutting said die to close one end of the molds which are opposite said tamper plunger and said compressor plunger.

3. In a briquetting machine, a rotatable die having one or more sets of briquette molds therein, each set including four molds equally spaced around the axis of said die, a reciprocating head carrying one or more sets of plungers movable parallel to the said axis of said die, said plunger sets including a

tamper plunger, a compressor plunger and an ejector plunger, said plungers being spaced to coincide with three of the four molds, and a heater for said die spaced relative to said plungers to play upon the fourth mold, means for reciprocating said plungers toward said die and to retract the same and for rotating said die to move a given mold from alignment with one plunger to alignment with the next plunger during the retracting movement of said plungers.

4. In a briquetting machine, a rotatable die having one or more sets of briquette molds therein, each set including four molds equally spaced around the axis of said die, a reciprocating head carrying one or more sets of plungers movable parallel to the said axis of said die, said plunger sets including a tamper plunger, a compressor plunger and an ejector plunger, said plungers being spaced to coincide with three of the four molds, and a heater for said die spaced relative to said plungers to play upon the fourth mold, means for reciprocating said plungers toward said die and to retract the same and for rotating said die to move a given mold from alignment with one plunger to alignment with the next plunger during the retracting movement of said plungers, means yieldingly connecting said tamper plunger to said reciprocating head, and a material inlet mounted between said tamper plunger and said die.

5. In a briquetting machine, a rotatable die having one or more sets of briquette molds therein, each set including four molds equally spaced around the axis of said die, a reciprocating head carrying one or more sets of plungers movable parallel to the said axis of said die, said plunger sets including a tamper plunger, a compressor plunger and an ejector plunger, said plungers being spaced to coincide with three of the four molds, a heater for said die spaced relative to said plungers to play upon the fourth mold, means for reciprocating said plungers toward said die and to retract the same and for rotating said die to move a given mold from alignment with one plunger to alignment with the next plunger during the retracting movement of said plungers, a rotatable driving means for reciprocating said plunger toward said die and to retract them, and an intermittent gearing device connecting said driving means to said die to rotate the die to move a given mold from one plunger to the next during the retracting movement of the plunger.

6. In a briquetting machine, a rotatable die having one or more sets of briquette molds therein, each set including four molds equally spaced around the axis of said die, a reciprocating head carrying one or more sets of plungers movable parallel to the said axis of said die, said plunger sets including a tamper

- plunger, a compressor plunger and an ejector plunger, said plungers being spaced to coincide with three of the four molds, and a heater for said die spaced relative to said
3 plungers to play upon the fourth mold, means for reciprocating said plungers toward said die and to retract the same and for rotating said die to move a given mold from alignment with one plunger to alignment with the next plunger during the re-
10 tracting movement of said plungers, and a stationary anvil abutting said die to close the molds lying opposite said tamper plunger and said compressor plunger.
15 Signed at Los Angeles, Calif., this 10th day of October, 1930.
